UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,993, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

The body A of the design is between two borders, B B. The groundwork of each border is dotted, and superposed upon the same is an angular stripe, a, of undulating outline with step-like and oblong projections, as shown, giving it a rustic appearance. The groundwork of the body A is covered with zigzag stripes b, alternating in series with up- and -down stripes c. Every alternate stripe b c is dotted, and the remainder have horizontal dashes. Over these stripes b c are placed stems d, leaves e, flowers f, and bunches of grapes g, all of which have a gently-undulating outline, so that when properly colored and applied to ribbed or embossed paper the

design will closely resemble embroidery or tapestry work.
